CLAIM

The ornamental design for a sofa as shown and described.

DESCRIPTION

FIG. 1 is a perspective view of the sofa;

FIG. 2 is a front elevational view of the sofa;

FIG. 3 is a rear elevational view of the sofa;

FIG. 4 is a left side elevational view of the sofa; the right side of which is a mirror image;

FIG. 5 is a top plan view of the sofa;

FIG. 6 is a bottom plan view of the sofa; and,

FIG. 7 is a perspective view of the sofa in an extended position.

The broken lines immediately adjacent to solid lines illustrate claimed stitching. All other broken lines illustrate portions of the sofa that form no part of the claimed design.

1 Claim, 7 Drawing Sheets(56)
